(57) **CLAIM**

We claim the ornamental design for a loudspeaker, as shown and described.

DESCRIPTION

FIG. 1 is a rear, top, right perspective view of a loudspeaker according to the present invention;

FIG. 2 is a rear, bottom, left perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom view thereof.

The broken lines illustrate portions of the loudspeaker that form no part of the claimed design. The alternating dash-dot lines on the front lower portion of the loudspeaker represent a boundary and form no part of the claimed design.
